APPARATUS FOR REPAIRING AND
CORRECTING LEVELS

Henry J. Kleineschay, Fond du Lac, Wis.

Application November 10, 1937, Serial No. 173,919

3 Claims. (Cl. 33—174)

This invention relates to a method of and apparatus for checking and repairing levels, straight edges and the like.

An important object of this invention is to provide a simple method and apparatus for supporting a level or straight edge on an adjustable support which has already been corrected by suitable means to conform to an imaginary line so that the gauge to be corrected may be mounted thereon and corrected to conform thereto.

Another object of this invention is to provide improved means for supporting a plumb by which the apparatus may be trued.

Other objects and advantages of the invention will hereinafter become more fully apparent from the following specification of which the drawing forms a part, and wherein:

Figure 1 is a front elevational view of the invention.

Figure 2 is a side elevational view in fragment of the same.

Figure 3 is a front elevational view of the device mounted vertically.

Figure 4 is an enlarged vertical sectional view showing one unit of the invention.

Figure 5 is a horizontal sectional view on line 5—5 of Figure 4.

Figure 6 shows a clip to support a plumb for alining the apparatus, and

Figure 7 is an enlarged perspective view of the clip.

Referring more particularly to the drawing wherein like reference characters designate like or corresponding parts throughout, 10 designates generally a bench or other supporting surface on which is mounted the two units 11 of the level checking apparatus.

Units 11, which are identical, each comprise a threaded bolt 12 having at one end fastening means 13 preferably in the form of a wood screw and in its opposite end a kerf or slot 14 by which the fastening means 13 may be secured in the top of bench 10.

Mounted on bolt 12 is a locking nut 15 and a sleeve type adjustable nut 16 provided at one end with a head 17. A bracket or yoke 18 is provided with the portions 19 and 20. Portion 19 as seen in Figure 5 is provided with a slot 21 to receive bolt 12. Bracket 18 is mounted on bolt 12 with portion 19 clamped between locking nut 15 and the adjusting nut 16.

The bracket 18 extends upwardly and has a threaded opening 22 in portion 20, which portion is above and in substantially the same vertical plane as portion 19 when bracket 18 is mounted

on bolt 12. Mounted in opening 22 is a threaded clamping member 23 having at one end a knurled head 24 by which member 23 can be adjusted, and at its opposite end a reduced headed shank 25 on which is swivelly mounted a collar 26 having a depending annular flange.

The periphery of the adjusting nut 16 is knurled so that either or both of these nuts 16 can be adjusted to a predetermined imaginary line determined by a level 27 having a spirit vial 28. After nuts 16 have been adjusted, the nuts 15 are moved up to clamp nuts 16 in adjusted position. Another level 27 can then be positioned on heads 17 after which the clamping members 23 can be brought into clamping engagement 15 with the upper edge of the level 27 to hold it in position while being checked or repaired so that the vials 28 of the levels 27 will correspond.

In Figure 3 the units 11 are shown mounted in vertical relationship for the purpose of testing 20 and correcting the vials 29 mounted in openings 30 in level 27 and at right angles to vial 28. The nuts 16 are adjusted in the same manner as heretofore explained by means of an accurate level 27 after which the vials 29 of other levels 27 may 25 be clamped in position for checking and repairing.

In Figure 6 the units 11' comprising bolt 12 and nuts 15 and 16 are mounted as in Figure 3 for testing and correcting straight edges. In 30 this case a plumb support 31 comprising a spring clip 32, is frictionally clamped to the upper nut 16, and is provided with a reduced shank 33 which is offset upwardly from clip 32 and which is provided with a slot 34 at its free end to receive and 35 hold the line 35 of a plumb 36. The clip 32 is positioned so that line 35 will touch the tip of head 17 of the upper unit 11' after which the lower unit 11' is adjusted and locked so that line 35 will be likewise touching the lower nut 16 at 40 its tip 17. The units 11' are then ready for testing and repairing straight edges.

From the foregoing it will be seen that an apparatus has been provided by which an improved method may be employed for testing and 45 repairing levels and straight edges which will simplify the operation and always insure accuracy in the testing.

It is to be understood that the apparatus as shown is only intended to illustrate a preferred 50 embodiment, various changes may be resorted to without departing from the spirit and scope of the invention as hereinafter claimed. Furthermore, it is to be understood that other means may be used to carry out the method without 55

departing from the spirit and scope of the invention.

I claim as my invention:

1. In a device of the class described, a screw 5 having a reduced threaded shank at one end adapted to engage a support, an internally threaded adjustable member mounted on said screw, a nut positioned beneath said member to retain it in adjusted position, a yoke projecting 10 upwardly from said screw and having a slotted inturned end engaging the screw and clamped thereto by said adjustable member and nut, the opposite end of said yoke being bent parallel to its other end and provided with a threaded opening, and a set screw mounted in said opening to clamp one end of a level between said set screw 15 and adjustable member.
2. In a device for correcting and repairing levels, a supporting member having a threaded shank, a nut mounted on said shank, a socket nut mounted on said shank above said first mentioned nut, an arm having its opposite ends bent to form parallel flanges disposed at right angles 20

to the intermediate portion thereof, one of said flanges being slotted to engage said threaded shank to be clamped in engagement therewith by said nut, the other flange being provided with a threaded opening, and a set screw mounted in 5 said opening in a plane with said socket nut to cooperate therewithin clamping one end of a level, said socket nut being adjustable to vary the elevation of said level.

3. In a device of the class described, a screw 10 having a reduced threaded shank at one end adapted to be secured to a suitable support, a socket nut adjustably positioned on the upper end of said screw, a bracket, means cooperating with said socket nut to clamp and support said 15 bracket, a set screw adjustably mounted in the opposite end of said bracket in a plane with said socket nut to cooperate therewith in retaining one end of a spirit level in said device, said socket nut adapted to be adjusted to align the ends of 20 the level.

HENRY J. KLEINESCHAY.
